UNITED STATES PATENT OFFICE.

DAVID T. SINGLETON, OF WILLARD, GEORGIA.

BICYCLE SHOULDER-BRACE.

SPECIFICATION forming part of Letters Patent No. 601,530, dated March 29, 1898.

Application filed March 31, 1897. Serial No. 630,146. (No model.)

To all whom it may concern:

Be it known that I, DAVID T. SINGLETON, of Willard, in the county of Putnam and State of Georgia, have invented a new and Improved 5 Bicycle Shoulder-Brace, of which the following is a full, clear, and exact description.

My invention relates to a shoulder-brace for bicycles, or a device intended to be used to enable the rider to apply a greater force to 10 the pedals than that due to his own weight.

It consists of certain improvements which enable the device to be quickly cast off, if desired, and of certain improvements by 15 which the weight of the device and its cost may be reduced to a minimum.

The invention also consists of certain parts and details and combinations of the same, as will be more fully described hereinafter and then pointed out in the claims.

Reference is to be had to the accompanying 20 drawings, forming a part of this specification, in which similar characters of reference indicate corresponding parts in all the figures.

Figure 1 is a perspective view of a bicycle 25 and rider, showing my device in use. Fig. 2 is a perspective view, on a larger scale, of my device detached from the rider and bicycle; and Fig. 3 is a sectional elevation of the upper portion of my device.

My device has two hooks A, which are provided upon their under surfaces with pads A', so as to make the contact thereof with the shoulders less disagreeable than it would otherwise be. These hooks are made longer at 35 one end than the other, the longer end being used to make the attachment to the bicycle-frame. These longer ends of the device are so arranged as to come in front of the body of the rider, and to these longer ends the bars B are attached. These bars have an angular 40 bend in their center and a horizontal section which is provided with slots b', adapted to receive clamping-bolts b. The horizontal section B' of one of these bars is made so that

its edges overlap and engage the horizontal section B² of the other bar. This construction is clearly shown in Fig. 3, and provides for a horizontal adjustment of the hooks A and permits of such an adjustment as best 45 suits the user. To each of the bars B is attached a bar or strip C, which is also attached to a plate D. This section C may be made

either as a metal bar or as a strap. It should be so connected both to the bars B and the plate D as to have a swing sufficient to adjust itself to the different distances necessary between its attachments to the bars B, which will vary as the hooks A are moved to or from each other. A hook d is attached to the plate D and is adapted to receive a ring e, fastened 55 in the upper end of a strap made in two sections E and E', which are adjustable upon each other by a buckle in the usual way. To the lower end of this strap is connected a spring-hook F, which is adapted to be fastened 60 to the ring G, connected with a clamp consisting of two members H and H', pivoted to each other at h and adapted to embrace the upper horizontal bar of a bicycle-frame. The clamp is secured on said bar by a clamping-bolt J, passing through both sections of 65 the clamp.

In using my device the hooks A are placed over the rider's shoulders and the clamp H secured to the horizontal bar of the bicycle 70 in front of the saddle. These two are then connected by the strap E E', which has been adjusted to such a length as to accommodate the rider.

This device enables the rider to exert as 75 much pressure upon the pedals as he is able without straining the arms by lifting upon the handle-bars, and will thus facilitate mounting hills and any other work where a heavy pressure is desired upon the pedals. 80 In case of emergency the device may be readily cast off by throwing the hooks A off the shoulders, and this may also be done by casting the ring e off the hook d. The device is not attached to the rider in such a way but 85 that he may be very quickly freed therefrom, and it is thus not as likely to cause accident 90 as devices which are more permanently secured to the rider.

The rigid connection formed by the two 95 bars B prevents the inward drawing or cramping tendency upon the shoulders which would otherwise be caused by downward strain upon the converging straps. Being adjustable the width of this connection may be varied to 100 suit different people. The clamps H H' may be adjusted to any position upon the upper bar of the bicycle-frame to correspond with the necessities of different figures. Those

with corpulent figures will require it farther forward than others and this adjustment may be quickly made. Having thus described my invention, I claim as new and desire to secure by Letters Patent—

1. A bicycle shoulder-brace comprising two hooks for the shoulders, bars horizontally adjustable upon each other, attached to the front ends of the hooks, and a connector leading from the bars to the frame of the bicycle, substantially as described.
2. A bicycle shoulder-brace comprising two hooks for the shoulders, bars horizontally adjustable upon each other, attached to the front ends of the hooks, a hook, connections therefrom to each of the adjustable bars, and a connection between said hook and the bicycle-frame, substantially as described.
3. A bicycle shoulder-brace comprising two

hooks for the shoulders, bars horizontally adjustable upon each other attached to the front ends thereof, a clamp attachable to the bicycle-frame, a ring fixed thereto, and a strip connecting said ring with the shoulder-hooks, substantially as described.

4. A bicycle shoulder-brace comprising two hooks extending over the shoulders, bars horizontally adjustable upon each other attached to the front ends thereof, means for clamping said bars together, a hook, connections therefrom to each of the adjustable bars, a clamp attachable to the bicycle-frame, and a strip connecting said clamp and hook, substantially as described.

DAVID T. SINGLETON.
